UNITED STATES PATENT OFFICE.

ARMEN H. TASHJIAN, OF CLEVELAND, OHIO.

COMBINED CONDUIT, JUNCTION BOX, AND OUTLET BOX.

Application filed January 19, 1921. Serial No. 438,382.

To all whom it may concern:

Be it known that I, ARMEN H. TASHJIAN, a citizen of the United States, residing at Cleveland, in the county of Cuyahoga and State of Ohio, have invented a certain new and useful Improvement in Combined Conduits, Junction Boxes, and Outlet Boxes, of which the following is a full, clear, and exact description.

10 In the erection of new buildings and the alteration of old buildings, the architect is called upon to locate the receptacles or so-called outlets for the electric installations in the various rooms, and while he may be ever 15 so far-seeing, it still frequently happens that tenants taking the rooms find it very inconvenient to get their electrical apparatus so arranged as to suit their particular convenience and to involve the least possible exposure of conductors. For example, a tenant may want his desk at a certain place in the room, and may require a light at one place, a fan at another, and a telephone at another; also he may wish a certain location 20 for his call-bells and telegraph and messenger service. Under the plans at present in vogue, a certain number of outlet boxes with receptacles and plugs are permanently located at various fixed points at the base of 25 the walls of each room or office. Each outlet box is connected with the electric distribution panel with separate conduits run in the floor. To find these prearranged receptacles well located for every requirement of 30 every tenant is very unlikely; with the result that for every desired localization of a telephone, light, fan, call-bell or other office conveniences, either the conductors from the receptacles will have to be extended a considerable 35 distance in an exposed manner, or else extensive tearing up of floors and walls, rearranging of outlet boxes and conduits, and patching of finish has to be done to suit each requirement.

40 A complete electric connection to a given electric appliance requires—1st, a junction box at the junction of the leader conduit and the distribution conduits; 2nd, a distribution conduit or carrier of conductors, and 3rd, a 45 box to receive the receptacle and plug. The object of my invention is to provide a single element or device which fulfills the functions of all three devices above enumerated along any point in its length, and thereby

not only make one element accomplish the 55 functions of three different devices but also by being able to fulfill the said functions along any point in its length to eliminate the limitations of fixity of junction boxes and outlet boxes and the attendant expense 60 of alterations and repairs as recited herein-before.

Inasmuch as I have shown a variety of constructions embodying the principle of the invention, the accomplishment of the object of which is outlined in the preceding, it is enough to state here that the invention comprises a combined continuous conduit, continuous outlet box and continuous inlet or junction box for electric installations of 70 both high and low tensions, into which leader conduits may enter along any point desired, in which a number of conductors can be extended at pleasure, and from which service at any desired point may be had 75 without the use of any junction boxes or outlet boxes. Further the element is so built as will permit ready access to the conductors within, by the removal of the outer face piece of the structure, and when in place the 80 device provides, further, a necessary building finish in the form of a sanitary base, chair-rail or cornice.

In practical operation the device in one form or other is intended to be attached to 85 the walls of a room or office, as a base, chair-rail or cornice; leader conduits of high and low tension currents are extended and inserted into the proper raceway of the device along any point desired, and when the tenant 90 has designated the desired location of each kind of outlet wanted, the front face piece is removed, the necessary conductors are pulled through the leader conduits and extended in their respective raceways of the 95 device, and the conductors are tapped at the exact locations wanted and connected to proper outlet receptacles. Holes of proper size and location for each receptacle or bushing are then cut in the front face piece, and 100 said face piece replaced in its position and snapped shut, and receptacles and bushings properly attached to the face piece. The tenant then has the receptacles and outlets just where he wants same. The operation may 105 be repeated any time the tenant desires changes or additional outlets, with very slight effort and without destroying or muti-

lating, or otherwise defacing or bodily removing the device.

In the accompanying drawings illustrating the invention, in the several figures of which like parts are similarly designated, Figure 1 is a vertical section showing one embodiment of the invention in a base. Fig. 2 illustrates the introduction into such a device as that shown in Fig. 1 of the leader conduits for the different types of conductors. Fig. 3 is a section similar to Fig. 2, but with the face-piece detached. Fig. 4 is a horizontal section, substantially on line 4-4 of Fig. 2, showing an angle or corner 15 of a room. Figs. 5, 6 and 7 are vertical sections illustrating various modifications of the parent invention, but omitting the supporting means, which last may be such as shown in the other views. Fig. 8 is a vertical section showing the invention applied to a chair-rail. Fig. 9 is a similar section showing the leader conduits applied to such chair-rail, and with the face-piece of the chair-rail removed. Fig. 10 is a vertical section showing the invention applied to a cornice molding. Fig. 11 shows the structure of Fig. 10 with the face-piece removed and with the leader conduits applied. Fig. 12 is a vertical section of another modification of the base. Fig. 13 is a vertical section of the leader conduit coupling.

In the drawings I have shown some of the various ways in which the invention may be applied, but wish to be understood at the outset as appreciating the fact that builders' or architects' fancies or requirements, and also building regulations may involve modifications of which the invention is susceptible, for obviously its flexibility is very great.

40 In the preferred construction, whether for a base, a chair-rail, or a cornice, the invention is best embodied in a body portion suitably supported and divided longitudinally into two compartments or raceways forming 45 conduits for the conductors, a continuous inlet or junction box for leader conduits and a continuous outlet box for receptacles, and a removable face-piece which may be cut at any point to receive an outlet box or bush- 50 ing or other medium by which the distribution wires or conductors may be connected with the conductors in the conduits.

Referring to Figs. 1, 2 and 3, 1 indicates the body portion shown as of metal and 55 divided longitudinally by a partition 2 so as to form an upper conduit 3 in which high-tension conductors may be arranged, and a lower conduit 4 in which low-tension conductors may be arranged. This body 60 portion is provided at its front with a foot-piece or molding 5, which rests on the floor and supports the body portion at the proper elevation, and for further security, the body portion may be nailed or screwed to the wall 65 6 as indicated at 7. 8 is an upper molding

suitably secured as by a spring or springs 9 fastened to the ground-piece 10 of the plaster work, the portion 8 being so shaped as to shed water and moisture. The parts so far described are more or less permanent 70 and stationary. 11 is a detachable face-piece, in the instance shown, having the deflected bottom end 12 which is adapted to be inserted between the upturned lip 13 of the body portion and the molding 5, in such 75 way as to form a substantially tight joint against the entrance of water. 13^x is a spacer to space off the molding 5 from the bottom of the body portion. The upper end of this face-piece has a return bend 14 80 which extends in between the upper flange 15 of the body and the bottom end 16 of the molding 8, and is clamped in these parts by means of the action of the spring or springs 9 on the molding, so as to provide a 85 tight joint at this point.

Leader conduits 17 may be introduced into the bottom of the body portion as indicated in Fig. 2, and similar conduits 18 may be introduced into the top of the body portion so as to supply the respective kinds of conductors to the conduits in the body portion. The conductors so introduced may be extended through the conduits in the body portion by fishing or any other suitable procedure.

If in the erection of a building plugs or outlets be placed in the face-piece and a tenant finds them inconveniently placed, it is only necessary to depress the upper molding and lift the face-piece out of its socket at the bottom, and cut a hole in the face-piece at the point required by the tenant, and insert the necessary outlet fixtures and make the proper electrical connections, and then restore the face-piece by snapping it into place.

As indicated in Fig. 4, the body portion may be made in sections of any desired length, and these sections connected by inside thimbles 19.

By the construction described it will be observed that the body portion containing the conduits for the conductors is not disturbed and only the face-piece is disturbed 115 when an outlet of any approved kind is to be inserted at a particular point.

The general principle of the invention as thus explained, is susceptible of a variety of modifications, some of which are herein 120 shown and described. For example, Fig. 5 illustrates a body portion 1 divided into upper and lower chambers or conduits 3 and 4 by means of a bend 20 which takes the place of the transverse partition 2 of the 125 construction previously described. This body portion has the top 21 extending only part way across and then has the upright portion 22 which is formed with a socket 23 and the terminal extension 24. The bot- 130

tom of the body portion has at its front the upward extension 25 which has the down-turned return portion 26 at the top of which is a ledge 27 and at the bottom a trough 28 and the floor ledge 29. The face-piece 30 has the reverted top portion 31 which in effect is the front portion of the top of the body, and then is extended vertically at 32 and provided with the tongue portion 33 which is adapted to be sprung into the socket 23 to effect the engagement of the face-piece with the body in a detachable way, and this face-piece is continued outwardly by means of the inclined portion 34 and the molding 35 which overhangs the subjacent portion of the face-piece and extends up into contact with the wall. The lower portion of the face-piece is provided with a ledge 36 which rests on the ledge 27 of the body and is continued downwardly as a floor molding 37 and then reverted and provided with the lip 38 which engages the trough 28 of the body, so that the face-piece is engaged with the body by the spring connection at the top and the lip at the bottom, forming a secure union with the body and adapting the face-piece to be readily removed from the body whenever it is desired to install an outlet box or bushing.

Fig. 6 illustrates the construction shown in Fig. 5 at a joint of two sections, in which sleeves 39 and 40 are inserted in adjacent ends of the sections. In this joint the bolts 41 and 42 may be passed clear through the structure.

In Fig. 7 a further modification is shown. The body portion 1 is divided into upper and lower conduits 3 and 4 by a transverse partition 2, and the top of the body portion 40 is provided with a spring element 43 and an upstanding lip 44 and the bottom is provided with an upstanding lip 45 and a base molding 46 which may be permanently fastened to the body. The face-piece 47 has the extension 48 parallel with the extension 44 of the body to form a socket in which the lower end of the molding 49 is placed, and adjacent to the extension 48 is a flange 50 on the back of the face-piece which hooks into the spring 43 to connect the face-piece with the body at the top, while the bottom of the face-piece is provided with an offset flange 51 which engages the lip 45 of the body.

In these two modifications of the construction it will be observed that there is equal facility for attaching the face-piece without disturbing the body.

In Fig. 8 is illustrated a chair-rail construction, in which there is a body portion 60 divided by the transverse partition 53 into upper and lower conduits, the top wall of the body being provided with an upstanding lip 54 and the bottom wall being provided with a trough 55, and the face-piece 56 having a hook-like flange 57 which

hooks over the lip 54, and the lower portion of the face-piece having a flange 58 which engages the trough 55, the outside of the face-piece being extended below and concealing the joint. Obviously, the face-piece may be detached from the body by lifting it. The body may be fastened to the wall by any suitable fastening 59, and there may be a top molding 60 and a bottom molding 61 attached to the plaster ground 70 for the wall. As shown in Fig. 9, the leader conduits 17 and 18 may be introduced in the bottom and top walls of the body as in Fig. 2.

As shown in Figs. 10 and 11, the principle of the invention is applicable also to a cornice molding, and in this case the construction is substantially as shown in Figs. 8 and 9, excepting that the top molding 62 is modified to conform to any suitable design or usage; and as herein shown it may be attached to a ceiling ground 63 by means of spring or other clips or clasps 64. The molding may be set, or may be made responsive to spring action, so as to grip the upper edge of the face-piece in its connection with the body. So also the upper and lower moldings in the construction shown in Figs. 8 and 9 and the lower moldings as shown in Figs. 10 and 11 may have more or less elasticity or flexibility so as to exert spring action on the bottom of the body portion and face-piece.

The explanation of the construction shown in Figs. 10 and 11 is the same as that used in describing Figs. 8 and 9, and the same reference characters are used.

In Fig. 12 I have shown another form of the invention, in which the body portion 1 is made by folding a piece of metal upon itself to form the partition 2, and thus divide the base into an upper and a lower conduit, as before. The front portion 65 of the bottom is extended upwardly about midway of the lower conduit, and has its upper edge offset inwardly as at 66. The upper conduit is provided with a flange 15. The face-plate 67 is a substantially flat continuous piece provided with hooked upper end 68 which is in sliding engagement with the flange 15, and its lower end fits in the offset portion 66 of the front portion, so that this face-plate may be easily slipped out of place when access is desired to either conduit. There is a base-molding 69 attached by a screw or screws or other devices 70, to the portion 65, and the upper end of this base-molding in connection with the offset portion 66 forms a socket in which the face-plate 67 is secured. The coupling members 19 may be of any approved construction, preferably of suitable material folded upon itself, with the overlapping joints 71 and 72.

The top of the base may be provided with an upright 73 which engages and supports 130

the molding 8 and spring 9, and itself is fastened to the plaster ground.

The body portion in Fig. 12 has a bead 74 at the front of its bottom which serves to space off the base-molding.

As shown in Fig. 13, the conduit 17 may have a screwthreaded end 74, and such screwthreads provided with an abutment, flange, or collar 75 adapted to be arranged 10 on one side of the combined conduit, receptacle box and outlet box, and a nut 76 applied to the screwthreads on the other side of the base-piece, so as to effect an intimate clamping connection of the conduits with 15 the combined device. The foregoing description of the coupling members of the conduit 17 applies equally to the coupling members of the conduits 18.

As indicated in dotted lines in Fig. 4, the 20 entrance of the conduits 17 into the base is not confined to the angle, but may be effected at any point, and this fact renders the construction especially convenient and valuable.

25 As already sufficiently indicated, the invention is susceptible of wide variations in the details of construction to meet the requirements of installation and of architects and builders.

30 What I claim is:—

1. A building element, for the reception and distribution of electric conductors, and the reception of electric leader conduits and receptacles or outlets, comprising a sheet metal body portion having isolated conduits for high-tension and low-tension conductors, and a face-piece for said body portion adapted to be detached from the body portion without disturbing said body portion to receive and support at any desired point a suitable outlet mechanism for electrical connection with the conductors in the conduits and associated stationary means for permitting the detaching and replacing 45 of said face-piece, said element serving the threefold purpose of a continuous conduit, a continuous junction box, and a continuous outlet or receptacle box:

2. A building element, for the reception and distribution of electric conductors, and the reception of electric leader conduits and receptacles or outlets, comprising a sheet-metal body portion provided with a longitudinal partition by which said body portion is divided into two chambers, a detachable face-piece of perforable material, whereby an outlet may be placed at any desired point for obtaining current, and cooperating means on the body portion and face-piece for separably connecting the two, said element serving the threefold purpose of a continuous conduit, a continuous junction box, and a continuous outlet or receptacle box.

65 3. A building element, for the reception

and distribution of electric conductors, and the reception of electric leader conduits and receptacles or outlets, comprising a sheet metal body portion divided longitudinally into upper and lower conduits for the reception of electric conductors of different kinds or tension, a foot-piece for supporting the body portion, a yielding top molding cooperating with the upper portion of the body portion, and a detachable perforable face-piece in sliding connection with the bottom and top of the body portion, said element serving the threefold purpose of a continuous conduit, a continuous junction box, and a continuous outlet or receptacle box. 80

4. A building element, for the reception and distribution of electric conductors, and the reception of electric leader conduits and receptacles or outlets, comprising a sheet metal body portion divided longitudinally 85 into upper and lower conduits for the reception of electric conductors of different kinds or tension, a foot-piece for supporting the body portion, a yielding top molding, and a detachable perforable face-piece having a hook-like upper end adapted to engage the upper portion of the body portion and to be engaged by the yielding top molding, said element serving the threefold purpose of a continuous conduit, a continuous junction 95 box, and a continuous outlet or receptacle box.

5. A building element, for the reception and distribution of electric conductors, and the reception of electric leader conduits and 100 receptacles or outlets, comprising a sheet metal body portion divided longitudinally into upper and lower conduits for the reception of electric conductors of different kinds or tension, a foot-piece for supporting the body portion, a yielding top molding, and a detachable perforable face-piece having a hook-like upper end adapted to engage the upper portion of the body portion and to be engaged by the yielding top molding and 105 having its bottom end engaged by and between the bottom of the body portion and the foot-piece, said element serving the threefold purpose of a continuous conduit, a continuous junction box, and a continuous outlet or 110 receptacle box.

6. A building element, for the reception and distribution of electric conductors, and for the reception of electric leader conduits and receptacles or outlets comprising a sheet metal body portion divided longitudinally into upper and lower conduits for the reception of electric conductors of different kinds or tension, a foot-piece for supporting the body portion, a yielding spring-pressed top molding cooperating with the upper portion of the body portion, and a detachable perforable face-piece in sliding connection with the bottom and top of the body portion, said element serving the threefold purpose 125 130

- of a continuous conduit, a continuous junction box, and a continuous outlet or receptacle box.
7. A building element, for the reception and distribution of electric conductors, and the reception of electric leader conduits and receptacles or outlets, comprising a sheet metal body portion divided longitudinally into isolated conduits, a detachable perforable face-piece for enclosing the front of the body portion, a spring connection between the upper ends of the body portion and the face-piece, and a foot-piece forming a bottom support for the body portion and spaced apart from the body portion to form a socket adjacent thereto for the reception of the lower end of the face-piece, said element serving the threefold purpose of a continuous conduit, a continuous junction box, and a continuous outlet or receptacle box.
8. A building element, for the reception and distribution of electric conductors, and the reception of electric leader conduits and receptacles or outlets, comprising a sheet metal body portion divided longitudinally into isolated conduits, a detachable face-piece, and spring connections between said face-piece and the upper portion of the body portion, said element serving the threefold purpose of a continuous conduit, a continuous junction box, and a continuous outlet or receptacle box.
9. A building element, for the reception and distribution of electric conductors, and the reception of electric leader conduits and receptacles or outlets, comprising a sheet metal body portion divided longitudinally into isolated conduits, a detachable face-piece, and spring connections between said face-piece and the upper portion of the body portion, and a yielding connection between said face-piece and the lower portion of the body portion, said element serving the threefold purpose of a continuous conduit, a continuous junction box, and a continuous outlet or receptacle box.
10. A combined continuous conduit, a continuous junction box, and a continuous outlet or receptacle box for electric installations in buildings, having isolated compartments for conductors of different tension or otherwise, a perforable face-piece, and means for detachably connecting the two, the whole constituting a building element.
11. A combined continuous conduit, a con-
- tinuous junction box, and a continuous outlet or receptacle box for electric installations in buildings, having isolated compartments for conductors of different tension or otherwise, a face-piece, and means forming parts of the structure for separably connecting the two, said face-piece being adapted to be tapped at pleasure for access to the conductors in either compartment at any desired point, the whole constituting a building element. 60
12. A combined continuous conduit, a continuous junction box, and a continuous outlet or receptacle box made wholly of metal and comprising a body portion divided into a plurality of conduits to receive electric conductors, a face-piece adapted to be tapped at any point for connection with the enclosed conductors, and means forming parts of the structure for separably connecting the body portion and face-piece, the whole constituting a building element. 70
13. A combined continuous conduit, a continuous junction box, and a continuous outlet or receptacle box for electric installations in buildings, having isolated compartments for conductors of different tension or otherwise, a perforable face-piece adapted to be tapped at any point for leading-out conductors, means for detachably connecting the combined device and its face-piece, and a leader conduit clamped to the former, the whole constituting a building element. 75
14. A combined continuous conduit, a continuous junction box, and a continuous outlet or receptacle box for electric installations in buildings, having isolated compartments for conductors of different tension or otherwise, a perforable face-piece adapted to be tapped at any point for leading-out conductors, means forming parts of the structures for detachably connecting the combined device and its face-piece, and a leader conduit having a collar and a cooperating nut for clamping said conduit to the combined device, the whole constituting a building element. 80
- In testimony whereof I have hereunto set my hand this 17th day of January A. D. 1921.
